Almanac Bibliography of Medina County, Ohio

James Parkin.

The scholars referred to in these Letters, Patients and making
part of the same, containing a description in the words of their
Thomas Hollingshead, himself of his improvements in the machine for
rolling and drawing brass.

It is to be noted that these three persons shall never

Be it known that J. Thomas Bell of the County of Gloucester
of this his invented, a new & useful machine for hauling & drawing
glass and that the following is a full & exact description of the construction
and operation of the same as invented by me. The machine is intended
to be constructed of strong durable timber & blocks & is to be put in
operation either by hand or water power. It is composed of the following
principal parts. (1) A large cylinder made of bad iron, or
 wrought iron or wood, in a conical form & the usual bore of a telescope
 is to be attached to it, a curved board, hinged & used to receive the wire which is
 intended to be constructed after the design of the model & drawing
 here with submitted. The cylinder may be made from twelve to eighteen
 inches in diameter, & from one to seven feet in length, & may be an even or
 of a proportionable size to be composed of cast iron blocks with gullets
 from 4 to 6 of an inch in width & 3 of an inch in depth. It must open
 inwards upon the long triangular corner of the cone as will
 particularly appear in the model drawing; the cone to be made of
 the same dimensions of the cylinder & placed stationary, may be
 composed of bad iron, wrought iron, or wood with either of the
 points of iron to one inch in width & 1/2 of an inch in height, & pointed
 towards the cylinder, corner of the cone, so that it will be within
 the said cylinder. (2) A large pulley of the same timber as the
 cylinder, & made of wood, or iron, or wood & iron, & may be
 composed of two or three pulleys, & may be from twenty to forty
 feet in diameter, & may be placed in any convenient place.

1732
independently from the main body and from the junction of the
cylinders and the frame. The end of the main frame carries a
supporting roller bearing, in order that the action of the main shaft
will not be impeded. This is one of the descriptions, a copy of which
we are intimated to follow; the second one of the
apparatus is the following description of the shaking apparatus
before described as can be particularly seen by reference to the model
deposited in the Patent Office. The office of the model, is to separate
the chaff from the seed, after they have been separated by the opera-
tion of the cylinder & frame. The central part of the machine is in-
tended to have a broad frame, which will be supported by the shaking apparatus
the use of which will be to pass over the chaff, running with the
seed. The stones are deposited in the bottom of the machine, when
in operation, exposed by the feeder to the influence of the air
& current. When the above machine is run by hand, it is
operated by hand, or passing from a drum back off from which
the wheel of the feeder, by hand, & so will be sent by the wind
the stones, & is obtained when the machine is run by water
power. I claim as my own invention in the above described ma-
chine, its intended principal construction, the feeder, cylinder and
cylinders broad, & its claim to have improved the shaking
apparatus, so as to conduct to the operation of the machine
and claim as my own invention the use of the model of operation
of the whole machine.

Given under my signature at Boston the 11th day
of February 1842.
